ADAPTER FOR PRACTICING FIRING

Eric von Latscher-Latka and Adam Schmidt,
Vienna, Austria, assignors to Oesterreichische
Aga-Werke Aktien-Gesellschaft, Vienna, Aus-
tria, a company of Austria

Application November 28, 1936, Serial No. 113,316
In Austria December 4, 1935

19 Claims. (Cl. 124—11)

The present invention relates to apparatus adapted to be substituted in place of the breech of a gun so as to provide the firearm with means for practice firing wherein the conditions of cartridge firing are produced.

The known arrangements for practice firing by means of compressed air possess disadvantages in that they do not truly reproduce the steps taking place when actually shooting. In other words the prior practice devices lack means for producing the shocks caused by the explosion of the cartridges and the sequence of the recoil.

An object of the present invention is to avoid the disadvantages above mentioned and to construct the apparatus for practice firing in such a manner that the operations of the apparatus correspond exactly to the steps taking place when actually shooting.

The essential feature of the present invention consists in the provision of a piston, which is movably arranged in a cylinder and subjected to the action of a spring preferably a run-out spring so as to slide forward in the direction of firing. The piston controls a compressed air inlet towards the end of its forward movement and the piston is thrown back by means of compressed air against the action of the force of the spring. The piston thus performs a movement like that of a fired gun breech producing a shock similar to the recoil of a discharged gun.

Another feature of the arrangement according to the present invention resides in the fact that the piston controls practically simultaneously but independently from one another the compressed air inlets of the conduit leading to the barrel as well as to the cylinder, so that the bullet is fired and the recoil takes place practically simultaneously.

The compressed air, present in the compressed air control compartments, may be used also for supplying bullets to the charge chamber of the arm. Thus by supplying such air to a preferably screw-shaped bullet-magazine and allowing the same to operate intermittently against the bullets the projectiles may be moved into the charge chamber.

Exemplary apparatus for carrying out the present invention is illustrated by way of example on the accompanying sheet of drawings in which Fig. 1 shows in longitudinal section a light machine gun provided with an arrangement for practice firing and with a pneumatic bullet supply device. Fig. 2 shows partly in longitudinal section the compressed air control and the trigger-mechanism. Figs. 3, 4 and 5 are views of the

pneumatic bullet supply device attached to the gun shown in Fig. 1.

The breech may be removed from the light machine gun and in place thereof is fitted the arrangement for practice firing by means of compressed air. The piston 1, as shown in Fig. 1 is provided with a handle 2. The piston 1 corresponding to the breech-head, is secured to a disc 3 which is connected with the bolt 4 by means of a bayonet catch. The bolt 4 is subjected to the action of a spring 72, so that it forces forwardly the piston 1 against the stop of the trigger. A piston rod 5 is secured by a pin 6 to the piston 1. The piston rod 5 carries a control piston which extends forwardly and terminates in the form of a rod 7. The control piston consists of two members 8 and 8', which slide in a cylinder 12 and are connected with one another by a reduced middle portion 9. A channel 10 passes through the rod 7, branches and terminates at the circumference of the middle portion 9. A slide 11 is mounted for longitudinal movement on the rod 7 and guided within the cylinder 12. The rod 7 is provided with shoulders 13, 14, which are disposed at both sides of the slide 11, so that the reciprocating rod 7 is adapted to cooperate with and thus move the slide 11 to and fro within the cylinder 12. A spring 21 arranged in a circumferential groove of the control slide 11, bears against the inner face of the cylinder 12, and serves for retarding the movement of the control slide 11. The control slide 11 is provided with bores 22, in order to balance the air pressure within the cylinder compartments at both sides of the control slide.

A pin 15 passes through the cylinder 12 and extends towards the control piston. This pin 15 is mounted for longitudinal movement and serves for operating a valve 16 to control communication between a compressed air tank and compressed air channels located within the gun. The pin 15 is arranged in such a manner, that it projects towards and rests on the reduced part 9 of the piston, when the piston assembly is in the rearmost position of rest. The valve 16 controls the communication between the compressed air channel and an annular groove 17 of the cylinder 12, which is provided with two ports 18 and 19, leading to the interior of the cylinder. A compressed air outlet 20 is arranged near the forward end of the cylinder 12.

The shoulder 14 of the rod 7 constitutes the end of a cylindric enlargement 23, which slides in a sleeve. In front of the enlargement 23, the diameter of the rod 7 is reduced to the caliber of

5

15

20

25

35

40

45

50

55

an auxiliary barrel 25. The auxiliary barrel is inserted in a barrel 24 when practice firing, so that the end of the rod may enter into the auxiliary barrel. The bullet feed channel 43 of the projectile feeder terminates near the rear end of the auxiliary barrel 25 and the end of the reciprocating rod 7 slides past the inlet end of the feed channel, thereby pushing a bullet into the auxiliary barrel.

10 The finger-engaging portion of the trigger shown in Fig. 2 is provided with two abutments 28, 29 mounted on a slide 31, which is adapted to be moved in a longitudinal direction against the action of a spring 30. The movement of the 15 slide 31 is limited by the extension 32, when pressure is applied to the abutment 28. However if the trigger is pressed by means of the abutment 29, the extension 32 is shifted in such a manner as to permit movement of the slide 31 over a 20 longer distance. A double armed lever 33 is pivotally secured to the slide 31. The forward end 34 of the lever 33 operates a push rod 35 and the latter co-operates with levers 36, 37. The lever 37 is provided with a projection 38 for locking the piston 1 connected with the piston 8. During the firing of the first shot the lever 33 is forced downwardly, so that its end 34 is moved out of engagement with the push rod 35, whereby the projection 38 is moved again in engagement 25 with and locks the piston 1 immediately after the first shot has been fired. If the trigger is forced back by means of the abutment 29, the slide 31 is pushed farther backward than the movement obtained by pressure on the abutment 35 28. Thus the lever 33 remains in engagement with the push rod 35 during the firing of the first shot but slides from the abutment 34 on to the abutment face 39 of the lever 33 and the trigger remains in its disengaged position, so that not 30 only individual shots are delivered, but automatic firing takes place.

If the arrangement for practice firing is fitted into the gun, the lever 33 is frequently operated by the cylinder of the control piston in accordance with the construction of the gun and therefore it cannot be directly influenced by the moving parts of the discharge device (see Fig. 2). Therefore in cases of this sort, the compressed air present in the cylinder 12 is utilized for setting the lever 33 for automatic firing. The compressed air is effective at the moment when the piston 8 reaches its rearmost position by operating the lever 33 by means of a ball 40 and thereby effecting the adjustment from single firing 55 to automatic firing. The ball 40 is arranged with a relatively tight fit in a transverse channel 41 of the cylinder 12 and the ball 40 is movable in said channel. The ball is secured in the channel 41 against removal by an outer plate spring 42 60 and a constriction of the channel towards the inside.

In the new arrangement for practice firing, the projectiles are supplied solely by compressed air, by allowing the air present in the control 65 compartments of the discharge device to operate the bullet or projectile magazine. The latter is in the form of a screw-wound pipe 43, one end of which extends into a block 44 adapted to be secured to the gun, while the other end thereof 70 carries a socket 45 for the attachment of a charging chute 46 (Fig. 5). The socket 45 is adapted to be normally closed by a cap 47. The block 44 is secured to the machine gun by means of a screw 48. A channel 49 establishes communication 75 between the interior of the piston-cylinder

12 and the projectile feeding device, terminates in a hollow space around the screw-bolt 48 and communicates by way of a pipe 50 with the end of the projectile channel, which is located farther away from the gun-barrel. The channel 49 communicates by way of a channel 51 with the projectile channel just behind the entry of the same into the charging compartment. 52 designates a copper ring for tightly packing the compressed air channel. The charging chute 46 is V-shaped 10 in cross section and terminates in a charging pipe 53 which is constructed in such a manner, that the charging chute is slightly inclined towards the projectile channel. The charging pipe and the projectile channel are interconnected 15 without any projecting edges or appreciable bends, so that the projectiles or bullets may move from the charging channel into the projectile magazine without meeting with any obstruction. 20

The new arrangement operates in the following manner:—The breech is removed from the machine gun and in its place the discharge and control arrangement is inserted in simple manner. The auxiliary barrel and the bullet or projectile feeder shown in Figs. 3 and 4 are attached to the gun. The gun is then ready for firing. If the trigger is pulled, the spring 72 becomes operative and causes the piston 1 to jump forward thereby carrying with it the control piston 8, 8' and 9. When the piston-part 8 strikes against the pin 15, the compressed air valve 16 is opened and during its continued forward movement, the shoulder 13 of the control piston strikes against and moves forward the slide 11. During this operation, a bullet resting in front of the outlet of the bullet feeder is engaged by the rod 7 and pushed into the auxiliary barrel 25. If the control piston moves forward sufficiently far the rear edge of the piston-part 8' passes beyond the ports 18 of the compressed air channel 17, compressed air will pass into the annular space around the piston-part 9 and through the channel 10 and to the bullet, which is hurled out by the force of the compressed air. Simultaneously 45 or practically simultaneously, the ports 19 are uncovered by the slide 11, so that the compressed air enters the compartment in front of the control piston and forces the piston backward against the action of the spring 72. During the 50 backward movement, the control piston again closes the compressed air valve 16, so that the final phases of the backward movement take place under the influence of the force of the compressed air enclosed within the cylinder. Towards the end of the backward movement of the piston, the stop 14 engages the slide 11 and thus moves the latter backward, whereby the port to the channel 49 is uncovered and the compressed air passes through the latter and into the bullet 60 feeder. Usually only a very weak force of the compressed air is necessary for operating the pneumatic bullet feeder and therefore it may be advisable to provide outlets 20 in addition to the channels 49, or a vent may be arranged at any 65 convenient point in the compressed air supply line leading to the bullet-channel.

The channel 49 is uncovered by the slide 11 immediately after the rod 7 has cleared the outlet of the bullet feeder leading into the charging compartment. At this moment, the expanding air 70 flows from the cylinder 12 into the bullet-magazine and through the channel 50. The air acts from the rear against the bullet and in view of the clearances between the bullets and the wall 75

of the channel 43, the expanding air flows forward through the rows of bullets and also directly influences the bullets near the charging space. The expanding air also passes through the channel 51 and into the bullet magazine, thereby increasing the direct influence of the bullets near the charging space and slackening the bullets in the bullet channel. The bullets are thus prevented from jamming. In order that the compressed air entering the bullet magazine will not leave the gun by way of the barrel and thereby carry with it any bullet, a vent 71 is provided at the point where the bullet magazine passes into the charging space. Thus directly after the return movement of the charging rod, a bullet is forced toward the charging space and remains there until the beginning of the next discharging operation.

This arrangement for practice firing by means of compressed air may be used either in pneumatic guns or it may be inserted in existing fire arms. In the case last mentioned, if small changes are made for adapting the practice arrangement to the space at disposal in and to the operating members of the breech of the arm, the practice arrangement may be inserted without any reconstruction of the arm. Examples of such guns are machine guns of all calibers, light machine guns, machine pistols, semi- and full automatic infantry guns, tank guns, tank defense and aircraft defense guns.

What we claim is—

1. An adapter for practicing firing by means of compressed air from machine guns and other light guns and adapted for insertion in the gun in place of the breech, comprising a cylinder, a piston movably arranged in said cylinder, a spring pressing against said piston and having the tendency to force said piston in the direction of firing, said cylinder having an inlet for the admission of compressed air into the cylinder arranged in said cylinder near its forward end and controlled by said piston, said compressed air causing the backward movement of said piston against the action of said spring thereby producing a shock similar to the recoil of an actually firing gun.

2. An adapter for practicing firing by means of compressed air from machine guns and other light guns and adapted for insertion in the gun in place of the breech, comprising a cylinder, a piston movably arranged in said cylinder, a spring pressing against said piston and having the tendency to force said piston in the direction of firing, said cylinder having an inlet for the admission of compressed air into said cylinder arranged in said cylinder near its forward end, and a locking member controlled by said piston and controlling said inlet, said compressed air causing the backward movement of said piston thereby producing a shock similar to the recoil of an actually firing gun.

3. An adapter for practicing firing by means of compressed air from machine guns and other light guns and adapted for insertion in the gun in place of the breech, comprising a cylinder, a piston movably arranged in said cylinder, said piston having a compressed air channel partly passing through said piston and open at the forward end of the piston, a spring pressing against said piston and having the tendency to force said piston in the direction of firing, said cylinder having an inlet for the admission of compressed air into the cylinder arranged in said cylinder near its forward end and controlled by said pis-

ton, said compressed air causing the backward movement of said piston against the action of said spring thereby producing a shock similar to the recoil of an actually firing gun.

4. An adapter for practicing firing by means of compressed air from machine guns and other light guns and adapted for insertion in the gun in place of the breech, comprising a cylinder, a piston movably arranged in said cylinder, a spring pressing against said piston and having the tendency to force said piston in the direction of firing, a rod secured to and projecting forwardly from said piston having a channel passing therethrough and partly through said piston, a slide arranged on said rod, stops on said piston and said rod limiting the movement of said slide on said rod, said cylinder having an inlet for the admission of compressed air into said cylinder arranged in said cylinder and controlled by said slide, said compressed air causing the backward movement of said piston thereby producing a shock similar to the recoil of an actually firing gun.

5. An adapter for practicing firing by means of compressed air from machine guns and other light guns and adapted for insertion in the gun in place of the breech, comprising a cylinder, a piston movably arranged in said cylinder, said piston having a compressed air channel partly passing therethrough and open at the forward end of the piston, a spring pressing against said piston and having the tendency to force said piston in the direction of firing, said piston having an air channel arranged therearound, said cylinder having an inlet therein establishing communication between said air channel and the interior of the cylinder in front of said piston, a slide arranged in said cylinder in front of said piston and controlling said inlet, a valve controlling the admission of compressed air to said air channel, and means co-operating with said valve and said piston in order to operate said valve by said piston, said compressed air causing the backward movement of said piston thereby producing a shock similar to the recoil of an actually firing gun.

6. An adapter for practicing firing by means of compressed air from machine guns and other light guns and adapted for insertion in the gun in place of the breech, comprising a cylinder, a piston movably arranged in said cylinder, said piston having a compressed air channel partly passing therethrough and open at the forward end of the piston, a spring pressing against said piston and having the tendency to force said piston in the direction of firing, said piston having an air channel arranged therearound, said cylinder having an inlet establishing communication between said air channel and the interior of the cylinder in front of said piston, a slide arranged in said cylinder in front of said piston and controlling said inlet, a valve controlling the admission of compressed air to said air channel, and means on said piston operating at first said valve and thereafter said slide, said compressed air causing the backward movement of said piston thereby producing a shock similar to the recoil of an actually firing gun.

7. An adapter for practicing firing by means of compressed air from machine guns and other light guns and adapted for insertion in the gun in place of the breech, comprising a cylinder, a piston movably arranged in said cylinder, said piston having a compressed air channel partly passing therethrough and open at the forward

end of said piston, a spring pressing against said piston and having the tendency to force said piston in the direction of firing, said cylinder having an air channel arranged therearound, a slide arranged in said cylinder in front of said piston, said cylinder having an inlet therein controlled by said slide and establishing communication between said air channel around said cylinder and the interior of the cylinder in front of said piston, 10 said cylinder having a port controlled by said piston and establishing communication between said air channel around said cylinder and the compressed air channel passing through said piston, a valve controlling the admission of compressed air to said air channel, and means co-operating with said valve and said piston in order to operate said valve by said piston, said compressed air causing the backward movement of said piston thereby producing a shock similar to the recoil of an actually firing gun.

8. An adapter for practicing firing by means of compressed air from machine guns and other light guns and adapted for insertion in the gun in place of the breech, comprising a cylinder, a piston movably arranged in said cylinder, a spring pressing against said piston and having the tendency to force said piston in the direction of firing, a rod secured to and projecting forwardly from said piston, said rod having a channel passing therethrough and partly through said piston, a slide arranged on said rod, stops on said piston and said rod limiting the movement of said slide on said rod, said cylinder having an air channel therearound, said cylinder having an inlet there- 30 controlled by said slide and establishing communication between said air channel around said cylinder and the interior of the cylinder in front of said piston, said cylinder having a port controlled by said piston and establishing communication between said air channel around said cylinder and the compressed air channel passing through said piston, a valve controlling the admission of compressed air to said air channel, and means co-operating with said valve and said piston in order to operate said valve by said piston, said compressed air causing the backward movement of said piston thereby producing a shock similar to the recoil of an actually firing gun.

50 9. An adapter for practicing firing by means of compressed air from machine guns and other light guns and adapted for insertion in the gun in place of the breech, comprising a cylinder, a piston movably arranged in said cylinder, said piston having a compressed air channel partly passing through said piston and open at the forward end of said piston, a spring pressing against said piston and having the tendency to force said piston in the direction of firing, said cylinder having an air channel arranged therearound, a slide arranged in said cylinder in front of said piston, said cylinder having an inlet therein controlled by said slide and establishing communication between said air channel around said cylinder and the interior of the cylinder in front of said piston, a bullet receptacle at the front part of the adapter, means establishing communication between the interior of the cylinder in front of said piston and said bullet receptacle, said cylinder having a port controlled by said piston and establishing communication between said air channel around said cylinder and the compressed air channel passing through said piston, a valve controlling the admission of compressed air to said air channel, and means co-operating with said

valve and said piston in order to operate said valve by said piston, said compressed air causing the backward movement of said piston thereby producing a shock similar to the recoil of an actually firing gun.

10. An adapter for practicing firing by means of compressed air from machine guns and other light guns and adapted for insertion in the gun in place of the breech, comprising a cylinder, a piston movably arranged in said cylinder, a spring pressing against said piston and having the tendency to force said piston in the direction of firing, a rod secured to and projecting forwardly from said piston, said rod having a channel passing therethrough and partly through said piston, a slide arranged on said rod, a spring inserted in said slide and braking the movements thereof, stops on said piston and said rod limiting the movement of said slide on said rod, said cylinder having an inlet for the admission of compressed air into said cylinder and controlled by said slide, said compressed air causing the backward movement of said piston thereby producing a shock similar to the recoil of an actually firing gun.

11. An adapter for practicing firing by means of compressed air from machine guns and other light guns and adapted for insertion in the gun in place of the breech, comprising a cylinder, a piston provided with a reduced middle portion movably arranged in said cylinder, said piston having a compressed air channel therein beginning at said reduced middle portion and ending at the forward end of said piston, a spring pressing against said piston in the direction of firing, said cylinder having an air channel arranged therearound, a slide arranged in said cylinder in front of said piston, said cylinder having an inlet controlled by said slide and establishing communication between said air channel around said cylinder and the compressed air channel passing through said piston, a valve controlling the admission of compressed air to said air channel, and means co-operating with said valve and said piston in order to operate said valve by said piston, said compressed air causing the backward movement of said piston thereby producing a shock similar to the recoil of an actually firing gun.

12. An adapter for practicing firing by means of compressed air from machine guns and other light guns and adapted for insertion in the gun in place of the breech, comprising a cylinder, a piston movably arranged in said cylinder, a spring pressing against said piston and having the tendency to force said piston in the direction of firing, and said cylinder having an inlet for the admission of compressed air into the cylinder arranged in said cylinder near its forward end and controlled by said piston, means connected with the trigger mechanism and controlling the supply of compressed air, and a lever controlled by said means and operated for single or automatic firing.

13. An adapter for practicing firing by means of compressed air from machine guns and other light guns and adapted for insertion in the gun in place of the breech, comprising a cylinder, a piston movably arranged in said cylinder, said piston having a compressed air channel partly passing therethrough and open at the forward

end of said piston, a spring pressing against said piston and having the tendency to force said piston in the direction of firing, said cylinder having an air channel arranged therearound, a slide 5 arranged in said cylinder in front of said piston, said cylinder having an inlet controlled by said slide and establishing communication between said air channel around said cylinder and the interior of the cylinder in front of said piston, 10 said cylinder having a port controlled by said piston and establishing communication between said air channel around said cylinder and the compressed air channel passing through said piston, a valve controlling the admission of compressed air to said channel, means co-operating with said valve and said piston in order to operate said valve by said piston, 15 a bullet magazine attached to the gun and terminating in the gun-barrel, and a duct controlled by said slide and establishing communication between the interior of said cylinder and said bullet magazine.

14. An adapter for practicing firing by means of compressed air from machine guns and other light guns and adapted for insertion in the gun 25 in place of the breech, comprising a cylinder, a piston movably arranged in said cylinder, said piston having a compressed air channel partly passing therethrough and open at the forward end of said piston, a spring pressing against said piston and having the tendency to force said piston in the direction of firing, said cylinder having an air channel arranged therearound, a slide 30 arranged in said cylinder in front of said piston, said cylinder having an inlet therein controlled by said slide and establishing communication between said air channel around said cylinder and the interior of the cylinder in front of said piston, said cylinder having a port controlled by said piston and establishing communication between said air channel around said cylinder and the compressed air channel passing through said piston, a valve controlling the admission of compressed air to said channel, means co-operating with said valve and said piston in order to operate said valve by said piston, 35 a block fixed to the gun, a bullet magazine in the shape of a screw-wound tube attached with one of its ends to said block, a duct controlled by said slide and terminating in said block, and a pipe in communication with said duct and connected to the other end of said screw-wound tube for the supply of compressed air.

15. An adapter for practicing firing by means of compressed air from machine guns and other light guns and adapted for insertion in the gun 40 in place of the breech, comprising a cylinder, a piston movably arranged in said cylinder, said piston having a compressed air channel partly passing therethrough and open at the forward end of said piston, a spring pressing against said piston and having the tendency to force said piston in the direction of firing, said cylinder 45 having an air channel arranged therearound, a slide arranged in said cylinder in front of said piston, said cylinder having an inlet therein controlled by said slide and establishing communication between said air channel around said cylinder and the interior of the cylinder in front of said piston, said cylinder having a port controlled by said piston and establishing communication between said air channel around said cylinder and the compressed air channel passing through said piston, a valve controlling the admission of compressed air to said channel, means co-operating with said valve and said piston in order to operate said valve by said piston, 50 a bullet magazine in the shape of a screw-wound tube attached to the gun and terminating in the gun-barrel, a screw cap closing the end of the bullet magazine which is remote from the barrel, and a duct controlled by said slide and establishing communication between the interior of said cylinder and said bullet magazine.

16. An adapter for practicing firing by means of compressed air from machine guns and other light guns and adapted for insertion in the gun 55 in place of the breech, comprising a cylinder, a piston movably arranged in said cylinder, said piston having a compressed air channel partly passing therethrough and open at the forward end of said piston, a spring pressing against said piston and having the tendency to force said piston in the direction of firing, said cylinder 60 having an air channel arranged therearound, a slide arranged in said cylinder in front of said piston, said cylinder having an inlet therein controlled by said slide and establishing communication between said air channel around said cylinder and the interior of the cylinder in front of said piston, said cylinder having a port controlled by said piston and establishing communication between said air channel around said cylinder and the compressed air channel passing through said piston, a valve controlling the admission of compressed air to said channel, means co-operating with said valve and said piston in order to operate said valve by said piston, 65 a bullet magazine in the shape of a screw-wound tube attached to the gun and terminating in the gun-barrel, and a duct controlled by said slide and establishing communication between the interior of said cylinder and said bullet magazine.

17. An adapter for practicing firing by means of compressed air from machine guns and other light guns and adapted for insertion in the gun 70 in place of the breech, comprising a cylinder, a piston movably arranged in said cylinder, said piston having a compressed air channel partly passing therethrough and open at the forward end of said piston, a spring pressing against said piston and having the tendency to force said piston in the direction of firing, said cylinder 75 having an air channel arranged therearound, a slide arranged in said cylinder in front of said piston, said cylinder having an inlet therein controlled by said slide and establishing communication between said air channel around said cylinder and the interior of the cylinder in front of said piston, said cylinder having a port controlled by said piston and establishing communication between said air channel around said cylinder and the compressed air channel passing through said piston, a valve controlling the admission of compressed air to said channel, means co-operating with said valve and said piston in order to operate said valve by said piston, a bullet magazine in the shape of a screw-wound tube attached to the gun and terminating in the gun-barrel, a screw cap closing the end of the bullet magazine which is remote from the barrel, and a duct controlled by said slide and establishing communication between the interior of said cylinder and said bullet magazine.

18. An adapter for practicing firing by means of compressed air from machine guns and other light guns and adapted for insertion in the gun 10 in place of the breech, comprising a cylinder, a piston movably arranged in said cylinder, said piston having a compressed air channel partly passing therethrough and open at the forward end of said piston, a spring pressing against said piston and having the tendency to force said piston in the direction of firing, said cylinder having an air channel arranged therearound, a slide arranged in said cylinder in front of said piston, said cylinder having an inlet therein controlled by said slide and establishing communication between said air channel around said cylinder and the interior of the cylinder in front of said piston, said cylinder having a port controlled by said piston and establishing communication between said air channel around said cylinder and the compressed air channel passing through said piston, a valve controlling the admission of compressed air to said channel, means co-operating with said valve and said piston in order to operate said valve by said piston, a bullet magazine in the shape of a screw-wound tube attached to the gun and terminating in the gun-barrel, and a duct controlled by said slide and establishing communication between the interior of said cylinder and said bullet magazine.

5 piston movably arranged in said cylinder, said piston having a compressed air channel partly passing therethrough and open at the forward end of said piston, a spring pressing against said 10 piston and having the tendency to force said piston in the direction of firing, said cylinder having an air channel arranged therearound, a slide arranged in said cylinder in front of said piston, said cylinder having an inlet therein controlled by said slide and establishing communication 15 between said air channel around said cylinder and the interior of the cylinder in front of said piston, said cylinder having a port therein controlled by said piston and establishing communication 20 between said air channel around said cylinder and the compressed air channel passing through said piston, a valve controlling the admission of compressed air to said channel, means cooperating with said valve and said piston in 25 order to operate said valve by said piston, a bullet magazine attached to the gun and terminating in the gun-barrel, a duct controlled by said slide and establishing communication between the interior of said cylinder and said bullet magazine, 30 and a charging chute placed on to the end of the bullet magazine which is remote from the gun-barrel.

19. An adapter for practicing firing by means of compressed air from machine guns and other light guns and adapted for insertion in the gun in

place of the breech, comprising a cylinder, a piston movably arranged in said cylinder, said piston having a compressed air channel partly passing therethrough and open at the forward end of said piston, a spring pressing against said piston and having the tendency to force said piston in the direction of firing, said cylinder having an air channel arranged therearound, a slide arranged in said cylinder in front of said piston, said cylinder having an inlet therein controlled by said slide and establishing communication between said air channel around said cylinder and the interior of the cylinder in front of said piston, said cylinder having a port therein controlled by said piston and establishing communication between said air channel around said cylinder and the compressed air channel passing through said piston, a valve controlling the admission of compressed air to said channel, means co-operating with said valve, and said piston in 20 order to operate said valve by said piston, a bullet magazine attached to the gun and terminating in the gun-barrel, a duct controlled by said slide and establishing communication between the interior of said cylinder and said bullet magazine, 25 and a charging chute of V-shaped cross section placed on to the end of the bullet magazine which is remote from the gun-barrel.
